TREILLAGE

Jacob G. Braun, Chicago, Ill.

Application July 16, 1952, Serial No. 20,647

Term of patent 14 years

(Cl. D13—4)

The figure is a front elevation of a trellage embodying my design.

The back of the trellage presents the same appearance as shown in the figure.

I claim:

The ornamental design for a trellage, substantially as shown and described.
